UNITED STATES PATENT OFFICE.

ALPHONSE F. PIEPER, OF ROCHESTER, NEW YORK.

INSTRUMENT SUPPORT.

Application filed October 8, 1926. Serial No. 140,354.

My invention relates to instrument support particularly useful on dental units for receiving and automatically properly positioning instruments so that they may be 5 readily gripped by the operator to be in correct operating position in the hand without further manipulation. My invention is particularly desirable where tubes or sockets are utilized on the dental unit for normally 10 supporting the instruments which are connected by cords with power supplying terminals within the units, the cord being weighed so that upon release of an instrument after operation therewith, the cord 15 will be retracted and the instrument drawn back into its tube or socket. Under these conditions it is very desirable that the instrument will automatically assume its definite 20 proper position within the tube so that when it is to be used, it can be readily taken hold of with the correct operating grip.

The structure shown on the accompanying drawings embodies the various features of our invention. On such drawings

25 Fig. 1 is a side elevational view of a dental unit with instruments supported in tubes thereon;

30 Fig. 2 is an enlarged view, partly in section, of the tube structure and the engagement of an instrument therein;

Fig. 3 is a side elevational view of a cam or guide frame which is inserted in the tube body; and

35 Fig. 4 is a sectional view on line 4—4 of Fig. 3.

The dental unit pedestal 10 has at its upper end the instrument board 11 for the support of one or more tubes or sockets 12 in which are seated various dental instruments, instrument 13 shown being a hot air 40 syringe. The cord 14 connects at the outer end with the instrument and extends through the tube into the interior of the pedestal, its inner end being supported at 15 for the connection with power supply, as for example, compressed air or electricity. The cord loops around a pulley 16 from which is suspended the weight 17, this weighed pulley tending to keep the cord drawn into the 45 pedestal and returning the instrument to its holder when it is released after operating use thereof. As before stated, it is very desirable that the instrument will seat in a certain position within its tube. I accomplish this by providing a camway or guide-way within the tube which is engaged by

a pin extending from the instrument, the guideway sloping to a seat to which the instrument is drawn by the pull of the cord, engagement of the pin with the sloping guideway causing the instrument to turn and to assume its proper position in the tube. As shown in Figs. 2, 3 and 4, I provide the camway or guideway by inserting a bushing 18 in the tube whose upper edge 19 presents the 50 inclined surface to be engaged by the pin or stud 20 extending from the instrument 13. The bushing may be formed by bending a piece of sheet metal to circular cross section, the bushing holding itself securely in position in the tube by its spring action against the tube, and to prevent longitudinal displacement thereof an annular shelf or shoulder 21 may be provided in the tube 12. The 55 surface 19 may be formed by cutting the upper end of the bushing diagonally to form the downward inclined surfaces A and B which lead to the vertical edges C and D of the bushing, these edges being separated a distance to leave the slot E of a width to 60 accommodate the stud 20. The slot is narrowed at the lower end to leave the abutment or seat ends F and G against which the stud 20 comes to rest when the instrument has been drawn to its proper position within the 65 tube. When the instrument is placed in the tube or drawn thereinto by the weighted cord, if the stud 20 is in alignment with the slot E, the instrument will be drawn down 70 longitudinally to its seat and proper position within the tube. However, if the instrument is rotatably displaced from its proper position, the stud 20 will engage with either the inclined surface A or B and as the instrument is pulled downwardly the engagement of the stud on the inclined surface 75 will cause the instrument to be rotated until the stud is brought into the slot to thus guide the instrument to its proper seating position in the tube.

100 In Fig. 2 the stud 20 is shown in engagement with the inclined surface A and the instrument will therefore be rotated with the stud toward the right. If the stud were in engagement with the other inclined surface B, the instrument would be rotated in the opposite direction during its downward travel in the tube. The operator is thus always assured that the instrument will be in the proper position which will enable him 105 to immediately get the proper grip thereon for operating purposes.

The guiding surfaces of groove could be formed in different ways from that shown. For example, the entire tube structure could be molded and the guide surfaces and groove then form an integral part thereof.

Having described my invention, I claim the following:

1. In a dental unit, the combination of a support, an instrument socket on said support, an instrument for engaging in said socket, a power supply cord extending into said socket and connected with said instrument, the other end of said cord terminating within said support, means tending to draw said cord into said support whereby said instrument when released will be drawn into the socket, and means for rotating said instrument when it is pulled into said socket to cause said instrument to assume a determined normal position in said socket.
2. In a dental unit, the combination of a support pedestal, an instrument tube supported on said pedestal, an instrument for seating in said tube, a weighted power supply cord within said pedestal extending at its outer end through said tube and connected with said instrument, a guide stud on the instrument, and inclined guiding surfaces on the inside of said tube receiving said stud and causing rotational movement of the instrument during longitudinal movement thereof in said tube whereby said instrument will be guided to a determined normal seating position in said tube.
3. In a dental unit, the combination of a support pedestal, an instrument tube supported on said pedestal, an instrument for seating in said tube, a weighted power sup-

ply cord extending into said tube and connected with said instrument, the other end of said cord terminating within said pedestal, means tending to draw said cord into said pedestal whereby said instrument when released will be drawn into said tube, a guide stud on the instrument, and a bushing within said tube having inclined guiding surfaces for receiving said stud and causing rotational movement of the instrument during longitudinal movement thereof in said tube whereby said instrument will be guided to a determined normal seating position in said tube.

4. In a dental unit, the combination of a supporting pedestal, an instrument tube supported on said pedestal, an instrument for engaging in said tube, a power supply cord extending into said tube and connected with said instrument, the other end of said cord terminating within said pedestal, means within said pedestal tending to draw said cord through said tube and said instrument into the tube, a guide stud on said instrument, and a bushing within said tube, said bushing having a longitudinally extending slot terminating in a seat at its lower end and having its upper edge inclined toward said slot whereby when the instrument is drawn into said tube the stud will engage said inclined edge to be guided to said slot and to said seat while the instrument is moving longitudinally in said tube.

In witness whereof, I have hereunto subscribed my name this 4th day of October, 1926.

ALPHONSE F. PIEPER.
